WINDING APPARATUS

Filed Feb. 24, 1943

UNITED STATES PATENT OFFICE

2,353,653

WINDING APPARATUS

Cyril M. Croft and Alvin W. Bergeron, Cumberland, and Frederick G. Dodge, La Vale, Md., assignors to Celanese Corporation of America, a corporation of Delaware

Application February 24, 1943, Serial No. 476,892

8 Claims. (Cl. 242—76)

This invention relates to winding apparatus for textiles and the like, and relates more particularly to means for winding or batching fabrics onto a take-up roll or shell.

In prior Patent No. 2,307,880, there is described an apparatus for winding fabrics on to a take-up roll or shell in which there is provided a guide-roll adapted to move in an eccentric path. This eccentric movement of the guide roll causes the fabric passing over the surface therefor to slide from one end of the guide-roll or shell with the selvages of the fabric out of register or in staggered relation. Accordingly, the piling up of the selvages is overcome, resulting in the avoidance of turned and stretched selvages as well as excessively creased fabrics.

It is an object of this invention to provide improved means for causing one end of a fabric guide roll to move in an oscillatory path.

Other objects of this invention, together with certain details of construction and combinations of parts, will appear from the following detailed description and drawing.

In the drawing:

Figure 1 is a perspective view of an eccentrically movable guide roll constructed in accordance with this invention, showing the mounting of the guide roll and the means for causing one end of the same to move in an oscillatory path, and

Figure 2 is a diagrammatic side view showing the path of the moving fabric, the rolls over which the fabric passes, and the roll upon which it is wound or batched.

Like reference numerals indicate like parts throughout both views of the drawing.

In a fabric winding device wherein a guide roll constructed in accordance with this invention and having one end thereof adapted to be oscillated, is employed, the fabric 3 which is to be wound is passed, in the direction indicated by the arrows, over roller 4 which is provided with means, generally indicated by reference numeral 5, for causing one end of the same to move in an oscillatory path, in contact with idler guide rolls 6 and 7, over positively-driven guide roll 8, and is then taken up on a positively-driven roll or shell 9 mounted on shaft 11, thus forming a roll of fabric 12. The guide rolls 6, 7 and 8 are mounted on shafts 13, 14, and 15, respectively.

Referring more particularly to guide roll 4 and the means 5 for causing one end of the guide roll to move in an oscillatory path, the ends of guide roll 4 are provided with caps 16 of metal or other suitable material, said guide roll ends being cut

away or reduced in diameter in order that the cap surfaces may be flush with the surface of the roll 4. Extending through cap 16 are stub shafts 17 and 17', the latter of which is journaled in a self-aligning bearing 18 which is mounted on a bracket 19 for attachment to the framework of a winding machine.

Stub shaft 17 on the free end of roll 4 is journaled in a yoke 21 and carries for rotation therewith a worm 22. The worm meshes with and is adapted to rotate a gear 23 fixed on a shaft 24 journaled in middle portion of yoke 21. To the ends of shaft 24 are fixed discs 25. To the surface of each of discs 25, adjacent the periphery thereof, is pivotally attached a link 26, the other end of each link being pivotally mounted on a bracket 21 which is adapted to be rigidly attached to the framework of the machine.

The operation of this device is as follows:

When the fabric to be wound, or to be treated and wound, on the take-up roll 9 is passed over the surface of roller 4, the roller 4 is caused to rotate. This rotation of the roller causes the worm 22 to turn thereby rotating gear 23. Gear 23 in turn rotates shaft 24 and thereby discs 25. The rotation of discs 25 effected by the rotation of the shaft causes the discs to rotate about their pivotal points on links 26. This rotary movement of the discs relative to links 26 causes the yoke 21 to reciprocate thereby effecting an oscillation of the free end of roll 4 of guide roll 4. This movement of the roll, as stated above, causes the fabric passing over the same to move from end to end thereof, and on take-up roll or shell 9 the selvages of the fabric assume a staggered effect.

It is to be understood that the foregoing detailed description and drawing are given merely by way of illustration and that many variations may be made therein without departing from the spirit of our invention.

Having described this invention, what is desired to secure by Letters Patent is:

1. In a device for winding fabrics, the combination with means for positively feeding fabric to a take-up roll, of a guide roll adapted to be rotated by the moving fabric, and means actuated by the rotation of said guide roll for causing one end of said guide roll to move in an oscillatory path.
2. In a device for winding fabrics, the combination with means for positively feeding fabric to a take-up roll, of a guide roll adapted to be rotated by the moving fabric, said guide roll being relatively fixed at one end and vertically movable at the other end thereof, and means

actuated by the rotation of said guide roll for causing one end of said guide roll to move in an oscillatory path

3. In a device for winding fabrics, the combination with means for positively feeding fabric to a take-up roll, of a guide roll adapted to be rotated by the moving fabric, a shaft at each end of said guide roll, and means operatively connected to one of said shafts and actuated by the rotation of said shaft for causing said shaft to move in an oscillatory path.

4. In a device for winding fabrics, the combination with means for positively feeding fabric to a take-up roll, of a guide roll adapted to be rotated by the moving fabric, a shaft at each end of said guide roll, one of said shafts being journaled in a relatively fixed position and the other shaft being vertically movable, and means on said movable shaft actuated by the rotation of said movable shaft for causing said movable shaft to move in an oscillatory path.

5. In a device for winding fabrics, the combination with means for positively feeding fabric to a take-up roll, of a guide roll adapted to be rotated by the moving fabric, a shaft at each end of said guide roll, one of said shafts being journaled in a relatively fixed position and the other shaft being vertically movable, a worm fixed to and rotatable with said movable shaft, a gear cooperating with said worm, and means operatively connected to said gear for causing said movable shaft to move in an oscillatory path upon rotation of the guide roll by said moving fabric.

6. In a device for winding fabrics, the combination with means for positively feeding fabric to a take-up roll, of a guide roll adapted to be rotated by the moving fabric, a shaft at each end of said guide roll, one of said shafts being journaled in a relatively fixed position and the

5 other shaft being vertically movable, a worm fixed to and rotatable with said movable shaft, a gear cooperating with said worm, and means, including a plurality of discs movable by said gear, for causing said movable shaft to move in an oscillatory path upon rotation of the guide roll by said moving fabric.

7. In a device for winding fabrics, the combination with means for positively feeding fabric to a take-up roll, of a guide roll adapted to be rotated by the moving fabric, a shaft at each end of said guide roll, one of said shafts being journaled in a relatively fixed position and the other shaft being vertically movable, a worm fixed to and rotatable with said movable shaft, a gear cooperating with said worm, a shaft carried by said gear, discs fixed to said shaft, links attached to said discs and adapted to cause said discs to rotate eccentrically upon rotation of said guide roll by the moving fabric, whereby said movable shaft is caused to move in an oscillatory path.

8. In a device for winding fabrics, the combination with means for positively feeding fabric to a take-up roll, of a guide roll adapted to be rotated by the moving fabric, a shaft at each end of said guide roll, one of said shafts being journaled in a relatively fixed position and the other shaft being vertically movable, a worm fixed to and rotatable with said movable shaft, a gear cooperating with said worm, a shaft carried by said gear, discs fixed to said shaft, links eccentrically and pivotally attached to said discs and adapted to cause said discs to rotate eccentrically upon rotation of said movable shaft by said moving fabric, whereby said movable shaft is caused to move in an oscillatory path.

CERTIFICATE OF CORRECTION.

Patent No. 2,353,653.

July 18, 1944.

CYRIL M. CROFT, ET AL.

It is hereby certified that error appears in the printed specification of the above numbered patent requiring correction as follows: Page 2, first column, line 10, claim 3, for the word "shaft" first occurrence, read --guide roll--; line 20, claim 4, and second column, line 35, claim 8, for "movable shaft" read --guide roll--; and that the said Letters Patent should be read with this correction therein that the same may conform to the record of the case in the Patent Office.

Signed and sealed this 24th day of October, A. D. 1944.
